UNITED STATES PATENT OFFICE.

VICTOR HENRY CANHAM, OF GUELPH, ONTARIO, CANADA.

HEMMER-GUIDE FOR SKIRTS OF LADIES' AND CHILDREN'S DRESSES.

No. 837,382.

Specification of Letters Patent.

Patented Dec. 4, 1906.

Application filed February 15, 1906. Serial No. 301,326.

To all whom it may concern:

Be it known that I, VICTOR HENRY CANHAM, a subject of his Majesty King Edward VII, and a resident of the city of Guelph, in the county of Wellington and Province of Ontario, Dominion of Canada, have invented a new and useful Hemmer-Guide for the Skirts of Ladies' and Children's Dresses and Coats, of which the following is a specification.

The object of this invention is to provide an apparatus for regulating the length of ladies' and children's dress-skirts and coats and at the same time providing a form upon which the edge of the skirt can be formed into a level hem at any required height from the floor. I attain these objects by the mechanism illustrated in the accompanying drawings, in which—

Figure I is a perspective view of the front of my new or improved hemmer-guide. Fig. II is a perspective view of the back of my new or improved hemmer-guide. Fig. III is an elevation of the hemmer-guide, and Fig. IV is a top view of the same.

Similar letters of reference indicate similar parts in all the drawings.

It consists of a heavy suitably-formed base carrying two vertical wire posts united in a bridge or arch at the top. On these posts slides a horizontal riser-bar which can be secured at any required height by means of a set-screw at one end. The other end of this riser-bar carries the peculiarly-shaped hemmer-guide, which is the principal feature of this invention.

The base A a is L-shaped and is preferably made of heavy metal, so as to prevent its being readily overturned. It rests on the three projections e e e, which also give greater stability.

The vertical posts B B can be formed from one piece of wire rod, as shown, or may be joined by an arch or bridge at the top. They carry the riser-bar C, which when the set-screw c is slackened off may be readily moved up or down on the posts B B, the set-screw c serving to secure same to the post at any desired height.

The hemmer-guide D, which may be of 50 round, square, oblong, or any other suitably-shaped section of rod, rises vertically from one end, preferably the left-hand, of the riser-bar C for a short distance, as shown at D. It is then bent forward into an arch 55 shape, extending forward and beyond the riser-bar, as shown at D', and then bent sharply at right angles in an opposite horizontal direction, forming an entering wedge at the angle, as shown at D'', Fig. IV, and 60 curving slightly back toward and past the other end of the riser-bar C, forming a segment of a circle or a curved horizontal guide for the hem at the lower edge of the skirt or coat, while by means of the riser-bar C, upon 65 which it is carried, the guide-bar can readily be set at any required height from the floor.

In practice the edge of the skirt to be regulated and hemmed is folded over and under or round the horizontal curved guide-bar and 70 pinned or tacked in place ready to be sewed, the apparatus being moved round the bottom of the skirt or the skirt being revolved over it, so as to secure the same height from the floor all round, the hem thus formed 75 slipping or being pulled off the free end of the curved guide-bar as the apparatus or the skirt is moved.

It can also be used for regulating the length of men's coats, and one or both posts can be 80 graduated in inches, if desired.

What I claim as my invention, and desire to secure by Letters Patent, is—

The hemmer-guide consisting of a suitably-shaped base carrying two vertical posts on 85 which slides a horizontal riser-bar, locked by means of a set-screw and carrying a horizontally-curved guide-bar one end of which is free to allow the formed hem to slide off substantially as hereinbefore described. 90

In testimony whereof I have signed my name to this specification in the presence of two subscribing witnesses.

VICTOR HENRY CANHAM.
